CLAIM

The ornamental design for a sole for an orthopedic device, as shown and described.

DESCRIPTION

FIG. 1 is a perspective view of a sole for an orthopedic device showing my new design.

FIG. 2 is a front elevational view according to the sole of FIG. 1.

FIG. 3 is a first side elevational view according to the sole of FIG. 1.

FIG. 4 is a rear elevational view according to the sole of FIG. 1; and,

FIG. 5 is a second side elevational view according to the sole of FIG. 1.

The broken lines illustrate environmental structure of a sole for an orthopedic device and form no part of the claimed design.
